US0D1006790S

(12) **United States Design Patent** (10) Patent No.: **US D1,006,790 S**
(45) Date of Patent: ** *Dec. 5, 2023

(54) **HEADPHONES**

(71) Applicant: **GN AUDIO A/S**, Ballerup (DK)

(72) Inventors: **Philip Bellham**, Ballerup (DK);
Rasmus Trudslev Pedersen, Ballerup (DK);
Bill Zeng, Ballerup (DK)

(73) Assignee: **GN AUDIO A/S**, Ballerup (DK)

(*) Notice: This patent is subject to a terminal disclaimer.

(**) Term: **15 Years**

(21) Appl. No.: **29/866,141**

(22) Filed: **Aug. 30, 2022**

Related U.S. Application Data

(60) Division of application No. 29/829,473, filed on Mar. 4, 2022, now Pat. No. Des. 980,188, which is a continuation of application No. 29/738,556, filed on Jun. 18, 2020, now Pat. No. Des. 952,600.

(30) **Foreign Application Priority Data**

Dec. 19, 2019 (EM) 007433701-1-5

(51) **LOC (14) Cl.** **14-01**

(52) **U.S. Cl.**

USPC **D14/206**; D14/226

(57) **CLAIM**

The ornamental design for a headphones, as shown and described.

DESCRIPTION

FIG. 1 is a top perspective view of headphones showing the new design; the distal end of the headband, away from the ear piece, is a mirror image left/right; the mirror image is evident from the claimed design shown.

FIG. 2 is a front view thereof.

FIG. 3 is a rear view thereof.

FIG. 4 is a right view thereof.

FIG. 5 is a left view thereof.

FIG. 6 is a top view thereof; and,

FIG. 7 is a bottom view thereof.

The features shown in broken lines depict environmental subject matter only and form no part of the claimed design.

1 Claim, 6 Drawing Sheets
